1676X

N. LLOYD.

Cook Stove.

Patented Feb. 29, 1812.

10
Philadelphia

Personally appeared before
me the subscriber, one of the justices of the peace for
the City of Philadelphia, the within Hannah Richardson
andis Lloyd, and made oath, that he verily believes
himself to be the true and original Inventor or dis-
coverer, of the within mentioned improvement on Stoves.

In witness whereof I have hereunto sub-
scribed my name, this twenty ninth
day of January, in the year one thousand
eight hundred and twelve.

Jacob Baker Alderman

This is to Certify that the within mentioned
Mechanicensis Lloyd is a Citizen of the State of
Pennsylvania.

William G. Oliver

Joseph Ball

We the subscriber And we Epiphie do hereby certify
that we have examined the stove as improved by
W. Lloyd, of the City of Philadelphia and find it
in operation to answer fully, the description as
attached to the drawings

William G. Oliver

Joseph Ball

Andrew Epiphie
